(57) **CLAIM**

The ornamental design for a paddle latch, as shown and described.

DESCRIPTION

FIG. 1 is a front perspective view of a paddle latch showing my new design;

FIG. 2 is a front perspective view thereof, shown in alternate position;

FIG. 3 is a rear perspective view thereof;

FIG. 4 is a rear perspective view thereof, shown in alternate position;

FIG. 5 is a top plan view thereof;

FIG. 6 is a bottom plan view thereof;

FIG. 7 is a front elevational view thereof;

FIG. 8 is a rear elevational view thereof;

FIG. 9 is a right side elevational view thereof;

FIG. 10 is left side elevational view thereof;

FIG. 11 is a front perspective view of a second embodiment of a paddle latch;

FIG. 12 is a front perspective view of FIG. 11, shown in alternate position;

FIG. 13 is a rear perspective view of FIG. 11;

FIG. 14 is a rear perspective view of FIG. 11, shown in alternate position;

FIG. 15 is a top plan view of FIG. 11;

FIG. 16 is a bottom plan view of FIG. 11;

FIG. 17 is a front elevational view of FIG. 11;

FIG. 18 is a rear elevational view FIG. 11;

FIG. 19 is a right side elevational view of FIG. 11; and,

FIG. 20 is left side elevational view of FIG. 11.

The broken lines indicate unclaimed bottom and forms no part of the claimed design.

1 Claim, 8 Drawing Sheets
